HYDRAULIC TAPPET

Arthur B. Hubbard, Grosse Pointe Farms, and Alexander M. Fleming, Grosse Pointe Park, Mich., assignors to Chrysler Corporation, Highland Park, Mich., a corporation of Delaware

Application January 26, 1952, Serial No. 268,374

4 Claims. (Cl. 123—90)

Our invention relates to improvements in lifting mechanism or tappets for internal combustion engine valves, and has particular reference to mechanisms of the type which are self-adjusting and include fluid controlling means interposed between the lifter or cam and the valve stem, as hereinafter more fully set forth.

A principal object of our invention is to provide an improved lifting mechanism or tappet of the hydraulic type which is particularly characterized by quietness of operation.

Another object of our invention is to provide an improved hydraulic tappet which is also characterized by a relatively small number of movable parts compared to other hydraulic tappets known in the art.

Still a further object of our invention is to provide an improved hydraulic tappet which is easily manufactured due to the fact that the accuracy of machining the relatively movable parts is not required as it is in machining the parts of tappets commonly known in the art.

Another object of our invention is to provide an improved tappet which is simple in operation as well as economical to manufacture.

The invention deals with an improved hydraulic tappet which includes a tappet body and a plunger slidable within the body. The tappet body is constructed to communicate with the oil supply of the engine and to accommodate the formation of an oil cushion between engageable portions of the body and plunger. This oil cushion provides quiet operation of the tappet.

Other objects and advantages will become more apparent from the following description of several embodiments of our invention, reference being had to the accompanying drawings in which:

Fig. 1 is a fragmentary side elevational view of an internal combustion engine having a portion in section which illustrates our invention.

Fig. 2 is a fragmentary side elevational view illustrating, in section, a different position of the tappet shown in Fig. 1.

Fig. 3 is a transverse sectional view taken on the line 3—3 of Fig. 1.

Fig. 4 is a fragmentary side elevational view partly in section illustrating a modification of the tappet shown in Fig. 1.

Fig. 5 is a fragmentary side elevational view illustrating, in section, a different position of the tappet shown in Fig. 4.

Fig. 6 is a transverse sectional view taken on the line 6—6 of Fig. 4.

Fig. 7 is a fragmentary side elevational view partly in section illustrating a further modification of the tappet shown in Fig. 1.

Fig. 8 is a fragmentary side elevational view illustrating, in section, a different position of the tappet shown in Fig. 7.

Referring more particularly to Fig. 1, we have shown a fragmentary view of an internal combustion engine

2

which comprises an engine block, generally designated by the numeral 10, having a cylinder bore 12 which receives a piston 14 therein. The cylinder block 10 is provided with a water chamber 16 which surrounds the cylinder bore 12 as well as an oil chamber 18 which communicates with the engine lubricating system (not shown). The engine block is also provided with a tappet bore 20 which receives a hydraulic tappet generally designated by the numeral 22. The tappet 22 engages a cam 24 which is an integral portion of a camshaft 26, the latter being rotated by the internal combustion engine during operation. The mechanism for rotating the camshaft 26 is not shown for the purpose of simplicity. The engine block 10 is covered by a cylinder head, generally designated by the numeral 28, which pivotally carries a rocker arm 30. One leg of the rocker arm 30 is communicatively connected to the tappet 22 by a push rod 32, the adjustment between the push rod and the rocker arm 30 being accommodated by a set screw and lock nut assembly 34. The opposite end of the rocker arm 30 engages one end of a valve stem 36 which is slidably received within a valve stem bore 38 disposed within the cylinder head 28. The lower end of the valve stem 36 is integrally connected with a valve head 40 which is seated against a valve seat or a shoulder 42 at the mouth of an intake chamber 44. The chamber 44 communicates with the space surrounded by the cylinder bore 12. A coil spring 46 coacts between the cylinder head and the valve stem 36 to urge the valve head 40 against the seat 42.

Rotation of the camshaft 26 causes the hydraulic tappet 22 to ride up on the toe of the cam 24 to thereby transmit rocking motion through the push rod to the rocker arm 30. The rocker arm in turn urges the valve head 40 off its seat or shoulder portion 42 against the action of the spring 46 to effect opening or closing of the intake passage 44. The foregoing description has been set forth to describe the environment in which our improved hydraulic tappet operates and it should be remembered that applicants' invention resides in the hydraulic tappet and the particular form of valving means described is not described for the purpose of limiting the application of applicants' device.

Our improved hydraulic tappet as shown in Figs. 1, 2 and 3 comprises a tappet body or cylinder member 50 which is slidably disposed within the tappet bore 20 and which has a closed end 52 engaging the cam 24. The other end of the cylinder member 50 is open and is provided with a relatively large diameter bore 54 which extends from the open end and terminates at a relatively smaller bore 56 with a shoulder 58 disposed therebetween, the latter being substantially parallel to the closed end 52 of the cylinder member 50. The tappet body or cylinder member 50 is also provided with still a smaller bore 60 which is disposed between the bore 56 and the closed end 52 of the tappet body or cylinder member 50. The bore 60 is smaller in diameter than the bore 56 for the purpose of rigidifying the lower end of the cylinder member 50. The outer cylindrical surface of the cylinder member 50 adjacent the bore 56 is provided with an annular recess 62 which communicates with the oil chamber 18 through a passage 64 disposed in the engine block. The passage 64 is so constructed and arranged that it communicates with the upper portion of the annular recess 62 when the closed end of the tappet body or cylinder member 50 is riding on the heel of the cam 24. It will be noted when viewing Fig. 2 that the passage 64 communicates with the lower end of the annular recess 62 when the closed end 52 of the cylinder member 50 is riding on the toe of the cam 24. By this construction the oil lubricant which is under pressure and pumped by mechanism not shown to the oil cham-

ber 18 at all times delivers oil to the annular recess 62 even though the tappet body or cylinder member 50 is moving up and down. The oil is delivered to the inside of the cylinder member 50 through a passage 66 disposed in the cylinder member at the lower end of the annular recess 62 as more clearly shown in Figs. 1 and 2.

The tappet 22 is also provided with a piston member 68, the upper end of which is provided with a recess 70 which receives the lower end of the push rod 32. The piston 68 is provided with a relatively large diametered portion 72 which is slidably received within the relatively large diametered bore 54 in the upper end of the cylinder member 50. The lower end of the piston 68 is provided with a relatively small diametered section 74 which is slidably received within the relatively small diametered bore 56 of the cylinder member 50. The sections 72 and 74 are connected by a surface 76 which overlies the shoulder 58 formed between the bores 54 and 56 thereby forming a pocket between the piston 68 and the cylinder member 50.

The lower end of the piston 68 which is disposed within the cylinder member 50 is provided with an axially extending passage 78 which communicates with a radially extending passage 80, the latter terminating on the surface of the smaller diametered portion 74 which is immediately below the surface 76. The purpose of the passages 78 and 80 is to accommodate the flow of lubricant from the interior of the cylinder member 50 to the pocket formed between the shoulder 58 and the surface 76.

In operation, when the closed end 52 of the tappet is riding on the heel of the cam 24, oil is pumped from the chamber 18 through the passage 64 into the annular recess 62 and from this recess through the passage 66 into the interior of the cylinder member 50 below the piston 68. The oil is also forced through the passages 78 and 80 to the pocket disposed between the surface 76 of the piston 68 and the shoulder 58 of the cylinder member 50. The relatively large diametered portion 72 of the piston 68 is made to accommodate a slight clearance between its outer surface and the large diametered bore 54 located at the open end of the cylinder member 50. As a result the oil which is pumped to the pocket formed between the surface 76 and the shoulder 58 may leak upwardly and outwardly of the tappet between the large diametered portion 72 of the bore 54, the space 84 disposed in the cylinder block above the tappet being in direct communication with the oil sump of the internal combustion engine.

As more clearly seen in Fig. 2, when the closed end 52 of the cylinder member 50 rides up on the toe of the cam 24 during normal operation of the engine, the piston 68 and the cylinder member 50 are necessarily telescoped a small amount toward each other. At this movement the passage 80 is cut off from communication with the pocket formed between the surface 76 and the shoulder 58 by the upper extremity of the relatively small bore 56 of the cylinder member 50 and the surface 76 approaches the shoulder 58 effecting a dash-pot action herebetween. The excess oil is bled off through the small space between the walls of the bore 54 and the section 72. When this action occurs, a small amount of oil is trapped in the pocket formed by the surface 76 and the shoulder 58 thereby forming a cushioning layer of oil therebetween. This cushioning layer of oil prevents the lower edge of the section 72 of the piston 68 from sharply striking the shoulder 58 during normal relative oscillatory movement between the piston 68 and the tappet body 50. By preventing the striking blows of these parts, the noise which normally accompanies conventional hydraulic tappets is eliminated.

In Figs. 4 and 5 we have shown a modification of the form of the invention shown in Figs. 1, 2 and 3 and like numerals have been applied to like parts. In this form of the invention, a coil spring 90 has one end seated within the bore 60 of the cylinder member 50 and has

its other end engaging the bottom of the piston 68. The spring 90 is under compression and acts to urge the piston 68 out of the cylinder member 50. The annular recess 62' in this form of the invention is narrower than its counterpart 62 shown in the form in Figs. 1 to 3 for the purpose of eliminating the flow of pressure lubricant from the chamber 18 to the cylindrical member when the tappet rests on the heel of the cam 24. When the tappet is on the heel of the cam, pressure lubricant is not needed to maintain the piston under pressure since this action is accomplished by the coil spring 90. When, however, as viewed in Fig. 5, the tappet is engaged by the toe of the cam 24 and the oil cushion is needed between the surface 76 and the shoulder 58, the annular recess 62' comes into registration with the passage 64 to thereby effect the circulation of the pressure lubricant or oil in the same manner as set forth relative to Figs. 1 to 3.

In Figs. 7 and 8, we have shown another modification of our invention. The numeral 120 represents a tappet bore disposed in the cylinder block generally designated by the numeral 110. A hydraulic tappet generally indicated by the numeral 122 is slidably disposed within the tappet bore 120 and is engaged at its lower end by a cam 124 which is formed as an integral part of a camshaft 126. The hydraulic tappet 122 includes a tappet body or cylinder member 150 provided with a uniformly diametered bore 154 which extends from the open end of the cylinder member 150 to the closed end 152 of the cylinder member, the latter engaging the cam 124. The bore 154 slidably receives a piston 168 which has a first cylindrical section 174 disposed within the bore 154 and which has a diameter only slightly less than the diameter of the bore 154. The piston 122 is also provided with a second section 172 which is integrally connected to the first section by a neck portion 173. The second section 172 is of a cylindrical configuration and has an external diameter greater than the diameter of the bore 154 but smaller than the diameter of the tappet bore 120. The upper end face of the cylindrical member 150 presents a shoulder 158 which in cooperation with the underside of the second section 172 forms parallel surfaces for accommodating an oil cushion between the piston 168 and the tappet body or cylindrical member 150. The tappet body or cylindrical member 150 is provided with an annular recess 162 which communicates with the chamber 18 through the passage 64 to thereby accommodate flow of pressure lubricant to the recess 162. The passage 166 is provided in the side of the cylindrical member at the lower end of the annular recess 162 to facilitate the reception of oil into the bore 154. The pressure lubricant or oil continually urges the piston 168 out of the cylindrical member 150 and escapes from the cylindrical member 150 by seeping between the surface of the first section 168 of the piston and the surface of the bore 154 thereby causing a flow of pressure lubricant or oil between the shoulder 158 and the underside of the second section 162 to thereby effect an oil cushion at this location.

It will be seen in Figs. 7 and 8 that the passage 64 is in constant communication with the recess 162 thereby continually furnishing pressure fluid to the interior of the tappet body 150. This lubricant or oil urges the piston 122 out of the bore 154 and maintains a tight operative connection between the cam 24 and the push rod 32. The oil supplied to the tappet body 150 under pressure continually escapes between the section 174 and the bore 154 and flows over the shoulder 158. When the tappet rides up to the toe of the cam 124, the under side of the piston section 172 approaches the shoulder 158 and is cushioned by the ever present layer of oil which continually flows over this shoulder.

The oil cushion provided in all forms of the invention shown herein prevents noisy operation of the tappets since the oil provides a dash-pot action between the relatively movable parts. It should also be noted that in

two forms of the invention only two parts form the complete hydraulic tappet. This number of parts is relatively few compared with conventional hydraulic tappets known in the art.

While we have illustrated and described but three embodiments of our invention, it is to be understood that such is for the purpose of illustration only, and it is contemplated that those skilled in the art may modify certain details without departing from the spirit or scope of the invention as defined in the claims appended hereto.

We claim:

1. A valve lifting tappet including a cam engaging member comprising a cylinder having an inlet adapted for communicative connection with the pressure lubricating system of an internal combustion engine, said cylinder having a closed extremity at one end and a piston bore at its opposite end portion provided with an entrance surrounded by a shoulder portion extending transversely of said bore, and a piston member having a portion slidably mounted in said bore below said shoulder portion and adapted to be urged away from the closed end of said cylinder by the fluid pressure of said lubricating system, said piston member having a shoulder portion overlying said shoulder portion of said cylinder member in axially spaced relationship for accommodating the reception of a cushioning layer of lubricant between said shoulder portions and said piston being provided with a passage for accommodating the flow of lubricant from within said cylinder to the space between said shoulders.

2. A valve lifting tappet including a cam engaging member comprising a cylinder having an inlet adapted for communicative connection with the pressure lubricating system of an internal combustion engine, said cylinder having a closed extremity at one end and a relatively large diameter bore extending from the other end of said cylinder inwardly and terminating at a shoulder, said cylinder having a relatively small diameter bore extending inwardly of said cylinder from said shoulder, and a piston slidably disposed within said cylinder having relatively small and large diametered sections with a shoulder disposed therebetween, said small and large sections of said piston being disposed in a telescoping relationship with said small and large bores of said cylinder, respectively, said small section being provided with a passage for accommodating the flow of lubricant from within said cylinder to said shoulders to thereby form a cushioning layer of lubricant between said shoulders.

3. A valve lifting tappet including a cam engaging member comprising a cylinder having an inlet adapted for communicative connection with the pressure lubricating system of an internal combustion engine, said cylinder having a closed extremity at one end and a relatively large diameter bore extending from the other end of said cylinder inwardly and terminating at a shoulder, said

cylinder having a relatively small diametered bore extending inwardly of said cylinder from said shoulder, and a piston slidably disposed within said cylinder having relatively small and large diametered sections with a shoulder disposed therebetween, said small and large sections of said piston being disposed in a telescoping relationship with said small and large bores of said cylinder, respectively, the small section of said piston being provided with a passage which extends from the end of said piston disposed within said cylinder to a location directly adjacent the juncture of said small section and said shoulder disposed between said sections, for accommodating the flow of lubricant from within said cylinder to said shoulders to thereby form a cushioning layer of lubricant between said shoulders.

4. A valve lifting tappet including a cam engaging member comprising a cylinder having an inlet adapted for communicative connection with the pressure lubricating system of an internal combustion engine, said cylinder having a closed extremity at one end and a relatively large diameter bore extending from the other end of said cylinder inwardly and terminating at a shoulder, said cylinder having a relatively small diameter bore extending inwardly of said cylinder from said shoulder, and a piston slidably disposed within said cylinder having relatively small and large diametered sections with a shoulder disposed therebetween, said small and large sections of said piston being disposed in a telescoping relationship with said small and large bores of said cylinder, respectively, the small section of said piston being provided with a passage which extends from the end of said piston disposed within said cylinder to a location directly adjacent the juncture of said small section and said shoulder disposed between said sections, for accommodating the flow of lubricant from within said cylinder to said shoulders to thereby form a cushioning layer of lubricant between said shoulders the diameter of the large diametered section of said piston being predetermined relative to the diameter of the large diametered bore of said cylinder to accommodate leakage of said lubricant out of said cylinder.
